UNITED STATES PATENT OFFICE

154,441

DESIGN FOR A ROCKING OR FLOATING TOY

Harry A. Tomarin, Cincinnati, Ohio

Application August 20, 1946, Serial No. 132,677

Term of patent 14 years

(Cl. D34—15)

To all whom it may concern:

Be it known that I, Harry A. Tomarin, a citizen of the United States, residing at Cincinnati, in the county of Hamilton and State of Ohio, have invented a new, original, and ornamental Design for Rocking or Floating Toys, of which the following is a specification, reference being had to the accompanying drawings, forming part thereof.

Fig. 1 is a front elevational view of the rocking or floating toy, showing my new design;

Fig. 2 is a top plan view of the device shown in Fig. 1.

Fig. 3 is a side elevational view of the device shown in Fig. 1.

Fig. 4 is a bottom plan view of the device disclosed in Fig. 1.

The dominant portion of my new design is shown in solid lines in the drawing.

The small circles shown in Figs. 2 and 3 represent surface markings.

I claim:

The ornamental design for a rocking or floating toy, as shown and described.

HARRY A. TOMARIN.
